UNITED STATES PATENT OFFICE.

JOSEPH W. REESE, OF SALT LAKE CITY, UTAH.

RAIL CHAIR AND CLAMP.

1,113,048.

Specification of Letters Patent.

Patented Oct. 6, 1914.

Application filed February 16, 1914. Serial No. 819,112.

To all whom it may concern:

Be it known that I, JOSEPH W. REESE, a citizen of the United States, residing at Salt Lake City, in the county of Salt Lake and State of Utah, have invented certain new and useful Improvements in Rail Chairs and Clamps, of which the following is a specification.

My invention relates to rail clamping devices, and has for its object to provide a rail chair and clamp to secure the railway rails to metallic ties of the channel shape, which will hold each rail firmly without the use of spikes and that will provide the cushion support under the rail so much desired. These objects I accomplish with the device illustrated in the accompanying drawings in which similar letters and numerals of reference indicate like parts throughout the several figures and as described in the specification, forming a part of this application and pointed out in the appended claims.

In said drawings in which I have shown a substantial embodiment of my invention, Figure 1 is a plan view of one end portion of a channel tie in which my clamping device may be used. Fig. 2 is the other end portion of a similar tie with a portion of a railway rail fastened thereon with my improved clamp and rail chair. Fig. 3 is a vertical section thereof on line $x-x$ of Fig. 2. Fig. 4 is a side elevation of the device in place on a portion of a rail and showing the tie sectioned on line $z-z$ of Fig. 2. Fig. 5 is a view in perspective of one of the clamps. Fig. 6 is a view in perspective of one of the rail seats detached. Fig. 7 is an elevation of the device as modified to hold the meeting ends of two rails. Fig. 8 is a view in perspective of the clamps as modified to secure the meeting ends of two rails.

As illustrated in the drawings, a metal tie of channel shape, A, has portions of the bottom cut and struck up to form clamp engaging lugs B. A portion of the free end of each of said lugs is bent to conform to and contact with the upper side of a rod or bolt C which is riveted in the side walls a of the tie. A portion of each of said side walls a is cut out adjacent the rails, as at b , in order that the rail D will not contact with said side walls. A clamping rail support is provided in the channel of said tie near each end thereof, which engages and supports the rail D placed thereon. Each of said supports consists of two opposed clamp

members 1, shown in detail in Fig. 5. The toe portion 2 of each of said clamps, when in place in the tie, engages said lug B and below said bolt C. Said clamps are set at 60 an incline and curved or bent to engage with the upper side of the base flange d of the rail, and each has the end portion 8, bent at right angles to the base, to engage with the web portion c of the rail. The heel portion 3 of each of said clamp members is curved upwardly to form a seating channel, within which the end of the rail chair or seat 4 rests. Each of said seats 4 extends from one of said seating channels to the opposed one in the other clamp member 1, and supports medially thereon the rail D. Each pair of clamp members 1 with the respective rail-seat 4 constitutes a transverse truss support for the rail carried thereby 75 and as each is slightly resilient I thus provide a cushion support for the rails held thereon.

When the rails are in place and supported by the rail seats and clamps, the bolts 6 are 80 inserted through and fastened in the side walls a of the tie, each bolt bearing against the upper curved face of the adjacent clamp 1, to prevent unintentional removal of the clamp. When the rails are burdened with 85 the rolling stock the portion 8 of the clamps will grip the web portion of the rail and the greater the burden the firmer the grip will be on the rail. The clamps 1 and the rail seats 4 are made of sufficient width that the 90 edges thereof will contact with the side walls a of the tie. For use at the junction or meeting ends of two rails, the vertical portion 8 of the clamps is extended laterally in the form of a fish plate member 9, having 95 perforation 10 therein through which the usual bolts 11 may be fastened, as shown in Fig. 7.

Having thus described my invention I desire to secure by Letters Patent and claim:— 100

1. In combination with a metal tie of channel shape having portions of its bottom struck upward; of clamp engaging bolts secured in the side walls of said tie; curved clamp members bearing against said bolts 105 and bent to engage the web portion of a rail and provided with a transverse channel near the foot of each; and a rail seat with the ends carried in said transverse channels.

2. In combination with a metal tie of 110 channel shape having portions of its bottom struck upward; of clamp engaging bolts

fastened through the side walls of said tie; opposed clamp members bent to engage the web portion of a rail placed therebetween and to bear against said bolts and with one end of each resting on the bottom of the tie and provided with a horizontal transverse recess therein; and a curved rail seat with the end portions carried in said recesses.

3. In combination with a metal tie of channel shape with upstanding side walls and bolts secured therein across said channel; of clamp members arranged in pairs and bent to engage the base flange and web portion of a rail placed therebetween; a foot

portion on each clamp member adapted to 15 bear against one of said bolts and on the bottom of said tie; a heel portion of each clamp bent to form a transverse seat channel; and a curved rail seat with the ends engaged in said transverse channels and 20 supporting a rail.

In testimony whereof I have affixed my signature in presence of two witnesses.

JOSEPH W. REESE.

Witnesses:

SAM RANEY,
W. W. BARTON.
